UNITED STATES PATENT OFFICE.

WALTER E. AMBERG, OF CHICAGO, ILLINOIS, ASSIGNOR TO CHICAGO STEEL POST CO., OF CHICAGO, ILLINOIS, A CORPORATION OF ILLINOIS.

WIRE-FASTENER.

1,234,112.

Specification of Letters Patent. Patented July 24, 1917.

Application filed May 27, 1916. Serial No. 100,210.

To all whom it may concern:

Be it known that I, WALTER E. AMBERG, a citizen of the United States, residing at Chicago, county of Cook, and State of Illinois, have invented certain new and useful Improvements in Wire-Fasteners, of which the following is a specification.

This invention relates to a device for fastening fencing to the supporting posts, and 10 is especially adapted to secure wire fencing to metallic posts. The invention consists in the combination and arrangement of parts shown in the accompanying drawing and described in the following specification, and it 15 is more particularly pointed out in the appended claims.

In the drawing, Figure 1 is a front elevation of a fragment of fence post and attached fencing, showing fastening devices made according to this invention, in operating position; Fig. 2 is a fragmentary sectional view showing the position one of the fasteners assumes while being moved into place to secure wire to a metallic post; Fig. 3 is a 25 section on line 3—3 of Fig. 1 and shows one of the fasteners in operating position; Fig. 4 is a section on line 4—4 of Fig. 1, showing another view of the fastener illustrated in Fig. 3; and Figs. 5, 6, 7 and 8 are detail 30 views of the fastener showing the way it appears when viewed from different positions.

In the drawing, the numeral 1 designates a fence post preferably made of comparatively thin metal plates. The post may be of 35 any well known or suitable construction, the one shown in the drawing being formed of angle iron as illustrated in Fig. 4. The fastening device proper, designated by the numeral 2, comprises an open link, preferably 40 made of a short piece of wire having the ends 3 and 4 bent backwardly on the main body of the wire, as illustrated in Fig. 8. The ends of the wire, as shown in this figure, do not extend a sufficient distance back to lie in the 45 same plane transversely of the main body of the link, but terminate somewhat short of this plane, to leave a space which when measured in a direction parallel with the main body of the link, is somewhat less than the 50 thickness of the plate which constitutes the fence post. The hooks formed by the bent portions 3 and 4 do not lie in the same plane passing through the main body of the fastener, but are offset angularly relative to one 55 another, as shown in Fig. 5. Because of this

arrangement, the distance designated by the letter *a* in Fig. 5 is considerably greater than the distance designated by the letter *b* in Fig. 8, the distance *a* being considerably more than the thickness of the plate of which 60 the post is made, while the distance *b*, as previously stated, is less than this thickness. In the position in which the planes of the hooks are viewed in Figs. 5 and 8, the hooks are foreshortened transversely, so that they 65 do not appear in their true proportions. In Fig. 6 the end 4 is shown parallel with the plane of the paper, so that it appears in its true proportions. In Fig. 7 the hook is viewed in end elevation, thus showing more 70 clearly the angular position of the two hooks relative to one another.

The hooked ends of the fasteners are made of proper size and proportion so that when one of the fasteners is placed in position 75 shown in Fig. 2, it will just pass through the opening 5 in the fence post 1. While the fastener is being placed in position, the wire 6 occupies a place adjacent the lower edge of the opening 5 and the end 3 of the 80 fastener bears against the post just below the wire. In order for the fastener to pass through the opening, it is essential that all of the parts shall be in this position relative to one another. As the hooked end 4 passes 85 through the opening 5, it will drop down on the opposite side of the post and the hooked portion 3 will move into position over the wire 6, as shown in Fig. 3. As the wire 6 enters the hook 3, it has a tendency to rotate 90 the fastener about its main body as an axis, and turn the end 4 to one side, so that it bears against the surface of the post 1, as shown in Fig. 4. When the fastener is once in place, it will be apparent that it will be 95 practically impossible for it to become again removed, since the wire 6 holds the end 4 turned to one side, in position to bear against the plate of the post 1, and since the fastener drops by gravity below the position in 100 which it entered the opening. Of course the fastener may be moved upwardly opposite the opening, but even if this should happen, the fact that the end 4 stands at one side of the opening, prevents its becoming removed. 105 In practice, the fastener will never be again moved into the position shown in Fig. 2, and hence the wire will be permanently held in place. Another consideration which makes it all the more improbable that the fastener 110

may become reinforced, is the fact that a fence consists of a number of wires 6 as shown in Fig. 1, and that all of the wires are held in a fixed position relative to one another by stay wires such as are shown at 7 in Fig. 1. In this way all of the wires 6 are constrained to move together, and it is therefore all the more improbable that they would all move at once into a position in which the fasteners could be removed. Moreover, the wires and the fasteners will not be spaced exactly equally, and while most of the fasteners will rest on the bottom edge of the hole, some of them will be drawn upwardly against the upper edge of the hole, as is shown in the case of the bottom fastener in Fig. 1. This will prevent movement of the fence relative to the post, and hence will assist in preventing movement of the fasteners into position from which they may be removed from the openings. While ordinarily the considerations referred to will be sufficient to prevent removal of the fasteners, if desirable, the end 4 which has been passed through the opening, may be given an additional twist after it is in position, thus positively locking the fastener to absolutely prevent escape.

Preferably the hooked ends are made so that it is necessary to hold them in the position shown in Fig. 2 to permit them to pass through the openings 5. In some cases the hooked end may be closed a sufficient amount, however, so that it will enter the opening when held with the main body of the hook normal to the face of the post, in which case reliance will be placed in the change in the angular position of the hook to retain it in place. While it is preferable that the opening shall be made oblong, this is not essential however, and circular openings or openings of any other desirable shape may be used.

I claim:

1. In a securing device for wire fencing, a metallic post comprising a plate having an oblong opening therethrough, a fastener comprising a short piece of wire having the opposite ends thereof bent to form hooks arranged to lie in different planes, one of said hooks being proportioned to pass through said opening when held in one position relative thereto and thereafter to be moved into another position in which it bears against the outer surface of said plate to prevent withdrawal of said hook from said opening.

2. In combination, a metallic fence post

comprising a plate having an oblong opening therethrough, a fastening device arranged in said opening and having a hooked portion at one end thereof arranged to engage a fence wire at one side of said plate, and a hooked portion at the opposite end thereof offset to lie in a different plane from said first mentioned hooked portion and to engage the surface of said plate at the side thereof.

3. In combination, a metallic fence post comprising a plate having a plurality of oblong openings therethrough, a fencing having a plurality of wires to be secured to said post adjacent said openings, securing devices comprising short lengths of wire having the opposite ends thereof bent backwardly to form hooks in planes offset angularly from one another, said hooks terminating short of the central portion of said fastening device, one of the hooks of each device being arranged to engage a wire of said fencing and the other hook of each of said devices being arranged to pass through one of the oblong openings in said post when said hook is held in one position relative to said opening and to be moved into another position in which the end of said hook engages the surface of said plate opposite that to which said fencing is secured to prevent withdrawal of said hook from said opening, said fencing being arranged to normally hold said securing device in a position in which said last-mentioned hook engages the face of said plate.

4. A fence wire fastener comprising a shank having the ends thereof bent backwardly to form duplicate fastening hooks having their planes arranged at an oblique angle to one another, said hooks being arranged to interchangeably engage the fence to be supported and the fence supporting member.

5. In a fence wire fastening device, a fence support comprising a metal plate having an opening therethrough and a fastening device extending entirely through said opening and having the end portions thereof bent backwardly to form hooks arranged in planes at oblique angles to one another and having the end portions thereof arranged to bear against opposite surfaces of said plate.

In testimony whereof I have signed my name to this specification, on this 8th day of May, A. D. 1916.

WALTER E. AMBERG
